UNITED STATES PATENT OFFICE

104,752

DESIGN FOR A GAS BURNER

Philip J. Sonner, Winfield, Kans.

Application July 9, 1936, Serial No. 63,743

Term of patent 14 years

To all whom it may concern:

Be it known that I, Philip J. Sonner, a citizen of the United States, residing at Winfield, in the county of Cowley and State of Kansas, have invented a new, original, and ornamental Design for Gas Burners, of which the following is a specification, reference being had to the accompanying drawing, forming a part thereof.

Fig. 1 is a top plan view of a gas burner show-

ing my new design; Fig. 2 is an end view thereof; Fig. 3 is a side view; Fig. 4 is a cross-sectional view on the line IV—IV of Fig. 3; and Fig. 5 is a bottom view thereof.

I claim:

The ornamental design for a gas burner as shown.

PHILIP J. SONNER.
